ADJUSTABLE LADDER LEG

John Guy Brewer, Piedmont, Mo.

Application December 12, 1938, Serial No. 245,295

4 Claims. (Cl. 228—63)

The present invention relates to new and improved ladders and more particularly to an adjustable leg for use therewith.

The primary object of the invention is to provide an adjustable leg adapted for attachment to a step ladder whereby said ladder may be used with convenience and safety upon a stairway or other uneven surfaces and which may also be used on floors or other level surfaces.

10 A further object of the invention is to provide an adjustable leg adapted for attachment to a step ladder comprising a pair of telescoping members having means for holding the members in adjusted relation. A pair of arms associated with the telescoping members serve as a means for attaching the device to the side bars of the step ladder which arms are so formed as to be readily attachable and detachable from said ladder, and a brace or spacing means is also carried by the telescoping members the free end of which is adapted to contact a step of the ladder for retaining the telescoping members in spaced relation thereon.

15 The invention will be fully and comprehensively understood from a consideration of the following detailed description when read in connection with the accompanying drawing which forms a part of the application.

In the drawing—

20 Figure 1 is a side elevational view of a step ladder having the adjustable leg attached thereto and shown in use.

Figure 2 is a rear elevational view of the device shown in Figure 1.

25 Figure 3 is a vertical sectional view and illustrating the relation of the telescoping members.

Figure 4 is a longitudinal sectional view taken substantially on line 4—4 of Figure 1.

30 Figure 5 is a fragmentary sectional view taken on line 5—5 of Figure 2, and,

Figure 6 is a sectional view taken substantially on line 6—6 of Figure 3.

35 Referring to the drawing for a more detailed description thereof wherein there is illustrated the preferred embodiment of the invention, a step ladder is indicated generally by the reference numeral 10 and comprises parallel side bars 11 and a series of steps 12 secured thereto in the conventional manner. To complete the construction of the step ladder, a second pair of side bars 13 are pivotally attached at 14 to spaced braces carried by the top step 16. In the normal use 40 of the ladder, the side bars 13 swing about the

5 pivot 14 to form spaced leg members which provide a firm supporting structure.

When painters, paper hangers, or other artisans are working upon stairways, it is necessary to employ a ladder having an adjustable leg to be positioned on one of the steps of the stairs. The conventional step ladder or straight ladder is not adaptable for this use. However, by means of the present invention an adjustable leg can be attached to a step ladder or straight ladder thereby providing the necessary support for the painter or paper hanger working upon stairways. Referring particularly to Figure 3 of the drawing, it will be noted that the adjustable leg indicated generally by the reference numeral 17 comprises a hollow tube-like member 18 telescopically receiving therein the tube-like member 19 said members being held in adjusted relation by the fastening means 20. The extending end of the tube 19 is bent at an angle as indicated at 21 to 50 overcome the angle of the leg when contacting the stairs. A plate 22 is attached to the extending end of the tube 19 and carries thereon a shoe member 23, said shoe being formed of rubber or similar material to assure a firm gripping surface. The inner portion of the tube 18 has formed 55 therein a longitudinal groove 24 for receiving the projections 25 formed on the tube 19 which serve to maintain said tubes in true position for proper sliding relation.

50 It is preferred that the adjustable leg 17 be detachably connected to the ladder 10 and for accomplishing this purpose there is provided a plate 26 attached, by any desired means to the upper end of the tubular member 18 and extends laterally on both sides thereof to form projecting ends. Each end of the plate 26 is formed with an opening for receiving the arms 27 and 28 respectively, the upper end of said arms being bent substantially at right angles to form an offset portion for attachment to the side bars of the step ladder. The offset portion indicated at 29 is held on the side bar 11 by a wedge action and when placed on the ladder will firmly retain the arms in position thereon. In the formation of the arms 27 and 28, it is preferred that the offset portion 29 be substantially heavier than the major portion of the arms for providing the necessary wedging action.

55 The other ends of the arms 27 and 28 are journaled in ears 30 extending from and forming a part of the cylindrical sleeve 31 which sleeve is slidable on the tube-like member 18 and held in adjusted relation by the wing bolt 32. The arms

27 and 28 are affixed to the ears 30 by riveting or other means.

When using the adjustable leg member it has been found desirable to employ a brace to retain a proper angular relation between the ladder and the leg member and referring to Figure 4 of the drawing it will be noted that there is provided a brace in the form of laterally diverging members 33 and 34 pivotally secured to the extending ear 10 35' of the cylindrical sleeve 31. The braces 33 and 34 comprise hollow members slidably receiving therein the arms 35 and 36, the ends of which are fork-shaped as indicated at 37 for engagement with one of the steps 12 of the ladder, best 15 shown in Figure 1 of the drawing. It is to be understood that the arms 35 and 36 are adjustably supported within members 33 and 34 to accommodate the variation in the angle of the adjustable leg member and the ladder when 20 used on the steps of stairs.

When desiring to use the ladder with the legs of two different heights, the ladder is first folded as shown in Figure 1 of the drawing. The sleeve 25 31 is then loosened so as to be freely slidable on the tube-like member 18, whereupon the offset portions of the arms 27 and 28 are positioned on the upper ends of the side bars 11. The braces 33 and 34 are then brought into engagement with an appropriate step of the ladder and the 30 cylindrical sleeve tightened by means of the wing bolt 32 to the tube 18. The leg member 17 is then adjusted to the proper height by telescoping the tubes 18 and 19 and locking them in adjusted position by the locking screw 20. It 35 will thus be seen that a conventional step ladder or the like can be provided with an adjustable leg member that will permit adjusting the legs of said ladder to different heights thereby permitting its practical use on stairs.

40 Also it will be understood, of course, by those skilled in the art that variations in the hereinabove described device involving the substitution of substantial equivalents for the devices described are intended to be comprehended within 45 in the spirit of the present invention and that the invention is capable of extended application and is not confined to the exact showing of the drawing nor to the precise construction described and, therefore, such changes and modifications 50 may be made therein as do not affect the spirit of the invention nor exceed the scope thereof as expressed in the appended claims.

What is claimed as new is:

1. An adjustable leg for ladders comprising a 55 pair of telescoping members, a plate carried by

and extending laterally on each side of one end of said members, a pair of arms slidably disposed in said plate, one end of said arms having means for attachment to the ladder and the other end for attachment to said members, means for holding said members in adjusted relation, and means for retaining said members in spaced relation on said ladder. 5

2. An adjustable leg for ladders comprising a hollow tube-like member, a second tube-like member telescoping within said first member, means for holding said tube-like members in adjusted relation, a plate attached to the upper end of the hollow tube-like member and extending laterally beyond both sides thereof, a 15 sleeve slidably disposed exteriorly of said hollow tube-like member, an arm disposed in each end of said plate, one end of said arms having means for attachment to the ladder, the other end of said arms attached to said sleeve, and a pair of 20 forked arms pivotally connected to said sleeve for contact with said ladder for bracing and retaining said tubular members thereon.

3. An adjustable leg for ladders comprising, a hollow tube-like member, a second tube-like member telescoping within said first member, means for holding said tube-like members in adjusted relation, a plate attached to the upper end of said hollow tube-like member and extending laterally on each side thereof, a sleeve slidably disposed exteriorly of said hollow tube-like member, an arm disposed in each end of said plate and having means on one end thereof for attachment to the ladder, means for attaching the other end of said arms to said sleeve, and means 30 for retaining said telescoping members in spaced relation on said ladder. 35

4. An adjustable leg for ladders comprising, a hollow tube-like member, a second tube-like member telescoping within said first member, means for holding said tube-like members in adjusted relation, a plate attached to the upper end of the hollow tube-like member and extending laterally beyond both sides thereof, a sleeve slidably disposed exteriorly of said hollow tube-like member, an arm disposed in each end of said plate, one end of said arms having means for attachment to the ladder, the other end of said arms attached to said sleeve, and a pair of forked arms pivotally connected to said sleeve for contact with said ladder for bracing and retaining said tubular members thereon, said forked arms being slidably disposed in tube-like members diverging from said slidable sleeve. 45
